SHOCK ABSORBER

Herbert L. Gordon, Monroe, Mich., assignor to Monroe
Auto Equipment Company, Monroe, Mich., a corporation of Michigan

Filed Sept. 4, 1963, Ser. No. 76,464

Term of patent 14 years

(Cl. D14—25)

FIG. 2 is a top plan view thereof, and

FIG. 3 is a bottom plan view thereof.

The dominant features of my design reside in the portions shown in full lines.

I claim:

The ornamental design for a shock absorber, as shown and described.
